UNITED STATES PATENT OFFICE.

JOSEPH SYLVAN, OF CICERO, ILLINOIS.

WARM-AIR HEATING FURNACE.

Application filed January 30, 1922. Serial No. 532,643.

To all whom it may concern:

Be it known that I, JOSEPH SYLVAN, a citizen of the United States, and a resident of Cicero, in the county of Cook and State 5 of Illinois, have invented certain new and useful Improvements in Warm-Air Heating Furnaces; and I do hereby declare that the following is a full, clear, and exact description thereof, reference being had to the accompanying drawing, and to the letters of 10 reference marked thereon, which form a part of this specification.

This invention relates to improvements in warm air heating furnace and consists of the 15 matters hereinafter described and more particularly pointed out in the appended claims.

One of the objects of the present invention is to provide a heating furnace which is so constructed as to eliminate the escape 20 of gas, smoke, or dust from the interior of the combustion chamber, into the air heating space surrounding the same.

Another object of the invention is to so construct the furnace that its interior may 25 be quickly and readily cleaned, from the outside of the furnace, by a simple and efficient means, the accumulated soot and dust being directed into the fire pot to be consumed therein.

30 These objects of the invention, as well as others, together with the many advantages thereof, will more fully appear as I proceed with my specification.

In the drawing:—

35 Figure 1 represents a vertical section through a warm air heating furnace embodying my invention;

Figure 2 represents a horizontal section 40 through the furnace, taken on the line 2—2 of Fig. 1.

Figure 3 is a view in elevation of a cleaning device embodied in my improved furnace, and which will be more fully referred to later.

45 Referring now in detail to that embodiment of the invention illustrated in the accompanying drawing, 5 indicates as a whole, the combustion chamber and 6 the outer casing which encloses the combustion chamber 50 in such a manner as to provide an air space about the same. As shown herein, the furnace is of the "round" type as distinguished from the "square" or "rectangular" type.

55 The combustion chamber is made up of a plurality of sections, placed one upon the other, said sections having the usual tongue

and groove construction at their ends to prevent lateral displacement and to assist in making a good, tight joint between the sections.

60 7 indicates the ash pit section. This section is made of cast metal and has a horizontal base flange 8 which defines the outside diameter of the furnace, and inwardly and outwardly extending radial top flanges 65 9 and 10 respectively, of a diameter defining the desired grate bar opening at the top end of said section. The ash pit section has a second opening 11 at its front, for the removal of ashes therefrom, the top of this 70 opening being defined by a horizontal wall section 12. In the flange 9 is provided suitable openings to secure the rear end trunnions of the grate bars 13. The front ends 14 of the grate bars have bearing in clips 75 15 and 16 secured to the flange 9 and to the horizontal wall section 12 respectively. Each grate bar extension has a gear 17, so that all of the grate bars may be operatively connected together, the middle grate bar 80 having the usual squared end to receive the crank for rocking said grate bar.

85 18 indicates the cast metal fire-pot section which rests upon the ashpit section. Said fire-pot section tapers upwardly and 90 outwardly from the bottom end and has a lateral rectangular, tubular extension 19 at its front, arranged in the vertical plane of the ash pit opening 11. This tubular extension provides the fuel opening for the fire pot. Associated with the ash pot section and fire pot section is a front plate 20 which has openings to receive the extensions of said sections and finishes off the 95 front of the furnace. This front plate is secured to said extensions by bolt or screws, and carries the ash pit door 21 and the feed-door 22. Above the feed door, the front plate has an integral water pan 23.

100 Resting upon the top edge of the fire pot section, is a heat radiating section 24, preferably made of a plurality of radially arranged parts or segments. As shown herein, the said radiating section is made of two identical parts or halves 25, the ends of 105 which have bolting flanges 26 provided with tongues and grooves to insure proper fit between the two parts and prevent undue warping between said parts. Each part 25 of the heat radiating section has top, bottom and intermediate vertically spaced webs 27, 28 and 29 respectively which converge 110

or taper inwardly and upwardly toward the central vertical axis of the combustion chamber as a whole. The webs 28 and 29 are preferably integral with the fire pot parts 25 and are connected thereto at their outer bottom margins by radially disposed extensions 30 and 31 respectively, which are separated from each other by annular openings 32 and 33 respectively. The web 27 is made integral with web 28 and is connected thereto by semi-cylindric parts 34, struck about the inner top end of the intermediate web 29 as a center. The outer marginal part of the top web 27 is connected to the upright wall of the fire pot section but terminates short thereof as shown in Fig. 1. Thus the webs define a tortuous or zig-zag path or channel through which the greater part of the products of combustion must pass, to direct the heat thereof to the outer wall or shell of the radiating section.

Resting upon the radiator section is a dome section 35 which converges upwardly and inwardly, parallel with the web 27 of the radiating section to terminate in a vertically disposed, axially arranged tubular extension 36, which includes a bearing spider 37, the purpose of which will appear later. Engaged about the tubular extension 36 is the elbow end 38 of a rearwardly extending horizontal smoke conduit 39, the other end of which extends through a hole in the outer casing 6 to be connected up with a sheet metal pipe section 40 leading to the chimney.

Surrounding the fire pot section, radiator section and dome section, but spaced therefrom, is a sheet metal jacket made up of sections 41, 42 and 43 which rest the one upon the other, with inter-engaging rabbeted connections, the bottom sheet metal section 41 resting upon the flange 10 of the ash pit section. Said jacket defines a space about the top sections of the combustion chamber which is filled with a heat absorbing and retaining material 44, preferably granular, such as sand. This sand also acts to fill or seal such cracks or crevices as there may be between the sections and also such cracks as may develop in any of said sections, due to expansion and contraction. It also provides an effective seal against the escape of gases and dust from the combustion chamber into the air heating space about the same.

45 indicates a cast metal scraper (see Fig. 3) which is of such shape as to extend diametrically across and fit in the zig-zag passageways formed by the web 27, 28 and 29 of the radiating section and that part of the dome section 35 extending parallel therewith. This scraper has the notches 46, 47 to clear said webs and the edges of said scraper 65 substantially touch the associated surfaces.

The scraper is fixed to the bottom end of an upright axially disposed shaft 48, which bears in the spider 37 and extends up through the smoke conduit to bear at its top end in a bracket 49 fixed to the elbow end of said conduit. A bevel gear 50 is fixed to the top end of said shaft without the bracket and this bevel gear meshes with a similar gear 51 on the inner end of a forwardly extending horizontal shaft 52. The inner end 75 of the shaft 52 also bears in the bracket 49 and the other end thereof extends through and bears in the front part of the casing wall 6 where it is provided with any suitable means without the casing for rotating the 80 same, as for instance the hand wheel 53.

The casing 6 is cut away at the front to fit the front plate 20, and to the lateral margins of which it is attached in any suitable manner, providing a tight joint therebetween. Said casing has at its rear, near the bottom end, an air inlet pipe 54 and in the top wall of said casing are provided flanged openings 55 to receive the warm air conducting pipes 56, shown in dotted lines 90 in Fig. 1.

In operation the greater part of the products of combustion rising from the fire pot will follow the tortuous path between the webs of the radiating section so as to effectively conserve the heat thereof which is taken up by said radiating section. This heat is absorbed and retained by the sand jacket so that its shell or casing becomes heated. Air entering the casing through the pipe 54 becomes heated by contact with the sand jacket shell and rises to pass out through the pipes 56, 56. After the products of combustion have passed through the fire dome, they will pass out through the conduit 39 to the chimney. Such unconsumed products of combustion, as soot, will adhere to the webs of the radiating section and when it is so desired, the hand wheel 53 is given a turn or two so as to rotate the scraper 45 which will scrape the soot from the adjacent parts. This soot will fall back into the fire pot to be again burned. Thus excessive smoking at the chimney or stack is eliminated. No gas or dust can pass through the sand jacket to come into contact with the air being warmed, consequently the warmed air delivered to the living rooms is clean and free from dust or soot particles. The sand jacket will retain the heat for a long time after the fire has gone out, so that a substantial saving in fuel is accomplished.

While in describing my invention I have referred to certain details of mechanical construction and arrangement of parts, I do not wish to be limited thereto except as pointed out in the appended claims.

I claim as my invention:

1. In a warm air heating furnace, the combination of a combustion chamber includ-

- ing a fire pot section and a dome section, a casing enclosing the combustion chamber and providing an air space about the same, a sheet metal jacket made of sections spaced 5 from but surrounding the combustion chamber and extending from the bottom of the fire pot section to the top of the dome section thereof, where it is open at the top, and a filler of granular heat absorbing and 10 retaining material in the space between the combustion chamber sections and said sheet metal jacket sections.
2. In a warm air heating furnace, the combination of a combustion chamber made 15 up of ash pit, fire pot, radiating and dome sections, resting the one upon another in the order named, the ash pit section including an outwardly extending radial flange at its top end, a sheet metal jacket made up of 20 bottom intermediate and top sections which are associated with, but spaced from the fire pot, radiating and dome sections of the combustion chamber, the bottom sheet metal jacket section resting on the radial flange of 25 the ash pit section, and a filler of granular, heat absorbing and retaining material between said sheet metal jacket sections and the associated combustion chamber sections.
3. In a warm air heating furnace, in combination of a combustion chamber including a fire pot section, a dome section and an intermediate radiating section, said last named section having webs defining zig-zag passageways through which the products of 30 combustion must pass, and a device for removing accumulations from the surfaces of said webs, which webs direct the removed accumulations back into the fire pot section.
4. In a warm air heating furnace, the 35 combination of a combustion chamber including a fire pot section, a dome section and an intermediate radiating section, said last named section having webs defining zig-zag passageways through which the products of 40 combustion must pass, and a cleaning device capable of a rotary movement arranged in said zig-zag passageways for removing ac-
- cumulations from the surfaces of the webs defining said passageways, which webs direct the removed accumulations back into 50 the fire pot section, and means operable from without the combustion chamber for imparting a rotary movement to said cleaning device.
5. In a warm air heating furnace, the 55 combination of a combustion chamber including a fire pot section, a dome section and an intermediate radiating section, the said last named section being made up of a plurality of parts, each having webs defining zig-zag passageways through which the products of combustion must pass, and a cleaning blade in said passageways and capable of being rotated from without the combustion chamber for removing accumulations 60 from said webs which direct the removed accumulations back into the fire pot section.
6. In a warm air heating furnace, the 65 combination of an outer casing, a combustion chamber in said casing and defining therewith an air heating space, said combustion chamber including a fire pot section, a dome section and an intermediate section, a smoke pipe connected with the dome section and extending horizontally through the 70 casing, the dome section and intermediate section defining a zig-zag passageway for the products of combustion, a cleaner blade rotatable in said passageway, an upright shaft to which the blade is attached, a 75 bracket carried by the smoke pipe, in which the top end of the shaft has bearing, and a member extended through the casing, operatively connected to the shaft and operable from without the casing, for rotating the 80 shaft.

In testimony that I claim the foregoing as my invention, I affix my signature in the presence of two witnesses, this 24th day of December, A. D. 1921.

JOSEPH SYLVAN.
